SASH BALANCING CONSTRUCTION

Abraham Schnitzler, Chelsea, Mass.

Application August 6, 1932, Serial No. 627,795

15 Claims. (Cl. 292—79)

This invention relates generally to window construction wherein the window sash is designed to slide freely to open and closed positions, as well as to be held in any desired open position, 5 and particularly to an improved sash holding and balancing mechanism.

Among the objects of the present invention is the provision of a window construction wherein in the sash: is easily raised or lowered; is held 10 tight and without rattling in all positions; can be easily and quickly mounted in the window frame and removed therefrom; and can be readily counter-balanced to the desired extent without being removed from the window frame. Other 15 objects are to provide an improved sash-holding mechanism which is simple, sturdy, and compact; which can be installed with minimum labor as a unit in the window frame; and which need not be removed from the window frame in 20 the event that removal of the sash is necessary or that the mechanism is to be adjusted to vary its counter-balancing force on the sash. The sash-holding mechanism which I have devised is generally of the type comprising a roller, which 25 rides in a groove in the stile edge of the sash and which is yieldingly and tightly engaged in the groove by spring action for all positions of the sash.

Another object of the invention resides in the 30 provision of means for affording a substantially constant sash counter-balancing force for the various positions of adjustment of the sash, so that the effort exerted in raising the sash from any point need be substantially no greater than 35 from any other point.

It is a further object of the invention to provide means having the aforesaid uniform counter-balancing function and serving also to yieldably hold the sash in the desired position in 40 the window frame.

It is also an object of the invention to provide simple and readily accessible and operable means for retracting the counter-balancing means and holding the same retracted to enable 45 a sash constructed in accordance with the invention to be readily removed from and placed in the window frame.

In accordance with the general features of the invention, the counter-balancing instrumentalities include a spring arranged to press a sash engaging member in a ramp or tapered groove bottom of the sash stile so as to exert an upward thrust on the sash to overcome gravity. A connection between the spring and sash engaging member compensates for differences in 55

spring pressure resulting from engagement of the member with spaced portions of the ramp, so as to cause the member to exert substantially the same lifting or counter-balancing pressure on the sash notwithstanding different vertical adjustments of the sash. The mechanism may be adjusted to exert any desired pressure within a predetermined range to enable the same to be used with a variety of sash weights and sizes, so that, if desired, all sashes may be 10 formed with like grooves or ramps. The mechanism is arranged to enable the same to be adjusted without requiring its removal or the removal of the sash, and to be rendered inoperative when installation or removal of the sash is 15 desired.

With the foregoing and other objects and features in view, I shall now describe my invention in conjunction with an embodiment thereof shown in the accompanying drawing, wherein 20

Figure 1 is a front view of a window whose lower sash is equipped with the holding mechanism of the present invention, part of the window frame and sash being broken away.

Figure 2 is an elevation of an installed holding mechanism looking in the direction of the arrows 2—2 shown in Figure 1.

Figure 3 represents a section on the line 3—3 of Figure 2, and includes an upper corner of the sash in fully lowered position.

Figure 4 is a view similar to Figure 3, but with the sash in fully raised position.

Figure 5 is a fragmentary perspective of the sash with a stile groove exposed to view.

Figure 6 is a detail perspective, showing the 35 accessibility of the sash-holding mechanism for adjustment purposes.

My invention is illustrated in Figure 1 as applied to the lower window sash of a conventional window structure, but it will, of course, be understood that it can be embodied equally as well in the upper window sash and in other window structures. As best shown in this figure, the lower sash 1 is mounted for upward and downward sliding movement in suitable ways defined, 40 as ordinarily, by suitable guide strips fastened to the jambs 2 of the window frame. The sash-holding mechanism of the present invention includes an anchor plate 3, which, as shown, is of elongated rectangular form and can be secured 45 near its upper and lower edges, as by screws 4, to each of the jambs 2. To this end, a suitable opening is formed through each jamb, so that the mechanism on the back of the plate 3 may occupy the usual hollow space 5 in back of the 50

jamb. The edge portions 6 of the jamb bordering the jamb opening may be countersunk sufficiently so that the outer or front face of the plate 3 merges with and constitutes part of the flat surface against which a stile edge of the sash bears. A bell crank 7 is pivotally secured as by a pin 8 to suitably spaced brackets 9, which may be affixed as by screws 10 somewhat above the lower end of the plate 3. The lower end 10 portion of the crank 7 is bifurcated at 11 and supports a stud 12 on which a roller 13 is rotatably mounted against lateral movement between the fork elements. The upper end of the crank 7 is pivotally secured, as at 14, to the lower end 15 of a rod 15, whose upper end portion passes through a bearing member 16 tiltably secured to the back of the plate 3 somewhat below its upper edge. The rod 15 can thus be reciprocated to cause movement of the crank 7, the plate 3 20 having a vertical slot 17 through which the roller and the lower end portion of the crank may swing outwardly. As shown, the bearing member 16 is provided with pins 18 entering into suitable openings or slots 32 in brackets forming 25 part of a U-shaped piece 19 affixed to the back of the plate 3. The slots 32 may extend upwardly from the lower ends of the brackets, thereby permitting the bearing member to be taken out when it becomes worn, and replaced by a new 30 one. It is, however, normally held in position to permit only tilting movement thereof, by a compression spring 20 encompassing the rod 15 and reacting between the bearing member 16 and a collar 21 affixed near the lower end of 35 the rod. The collar 21 is preferably in threaded engagement with the rod 15, so that its turning permits of an adjustment of the spring compression. It is desirable that this adjustment be made from the outside of the window frame and 40 without necessitating a removal of the sash or sash-holding mechanism. Accordingly, as shown in Figure 6, I may provide the collar 21 with spaced apertures 22, which become accessible from the outside of the window frame by merely 45 removing a screw closure 23 normally kept in the aperture 24 formed through the plate 3 immediately in front of the collar 21. With the closure 23 removed, it is possible to insert a rod, screw driver, or other tool into the apertures 22 and to turn the collar 21 for the purpose of either increasing or reducing the compression of the spring 20. The spring tends to cause the rod 15 to translate downwardly, thereby forcing the roller 13 to swing outwardly 50 through the opening 17 in the plate 3.

The roller 13 is engaged within a groove 25 in the edge of the corresponding sash stile 26, thereby serving to minimize the friction encountered in raising or lowering the sash. It is advantageous that each groove 25 be of gradually increasing depth from the upper edge of the sash to its lower edge, as this means that the spring-pressed roller will constantly tend to raise the sash and to overcome the effect of gravity 65 thereupon. To the base of each groove 25 is preferably fastened a suitable metal strip 27, which furnishes a smooth, wear-resistant surface for the roller 13.

When the sash is in its fully lowered position, 70 as shown in Figures 1 and 3, the roller 13 is engaged within the groove 25 at its upper end, which is of slight depth, so as to permit removal of the sash in a manner presently to be described. With the sash in its fully raised position, as shown in Figure 4, the roller 13 is

swung outwardly and is engaged within the groove 25 at its lower end of maximum depth. The tilttable bearing 16 permits the rod 15 to move freely from its substantially vertical position shown in Figure 3 to the inclined position 5 shown in Figure 4.

The compression of the spring 20 is preferably adjusted so as to counter-balance the effect of gravity and thus hold the sash in any desired raised position. As already indicated, the compression of the spring and its counter-balancing action may be accurately and quickly adjusted by turning the collar 21, which is accessible from the outside of the window frame. Unless the holding mechanism were provided with means for maintaining the roller 13 in its fully retracted position so as not to interfere with the sash, it would be exceedingly difficult to effect a removal of the sash without disturbing the sash-holding mechanism, on account of the comparatively 15 heavy compression necessary in the spring 20 for overcoming the weight of an ordinary window sash.

The construction and arrangement forming the subject matter of the invention are such as to 25 enable the counter-balancing unit to be made inoperative so that when installed it will not interfere with the initial installation of the sash and any subsequent removal and replacement of the sash. This involves a retraction of the roller 13 30 until it does not project beyond the outer surface of the anchor plate 3.

To this end, the rod 15 is provided in its upper end with an opening 28, and the bracket or anchor plate 3 is provided with a threaded opening 29 in which an adjusting element such as the screw 30 is disposed. When the sash is brought to its substantially fully lowered position, as seen in Figures 1 and 3, the roller 13 is forced farther and farther into the space 5 behind the jamb, 40 thus rotating the bell crank lever 7 clockwise and raising the rod 15 until its opening 28 is slightly out of axial alignment with the screw 30, the opening 28 being so arranged that its upper side is in the path of movement of the conical end 45 of the screw. As the screw 30 is rotated so as to move toward the rod 15, the conical end of the screw engages in the opening 28 and cams the rod upward, thus causing the crank 7 to rotate clockwise as seen in Figures 1 and 3 to such an 50 extent as to withdraw the roller 13 until it does not project outwardly beyond the outer surface of the plate 3.

It will be observed that only a slight raising movement of the rod 15 by the screw 30 is required to cause a substantial movement of the roller 15. This is due to the fact that when the pin 14, which turns about the pivot 8 as a center, is located adjacent its "zenith", it moves a substantial distance circumferentially although 60 its "vertical" distance from the pivot 8 is changed only slightly. This is illustrative of the well-known principle of harmonic motion. The axle 12 of the roller 13, because of its greater radius, moves throughout a somewhat greater arc than the pin 14, and because of its rotation adjacent its "zenith", moves laterally a distance almost 65 equal to its arcuate movement and certainly sufficiently to draw the roller clear of the sash 1.

Viewing Figure 3, it is clear that the rod 15 70 need be raised only a small fraction of the amount by which the roller 13 projects outwardly, in order to fully retract the roller.

As will be evident from the drawing, the spring 20 is expanded as the sash 1 is raised from its 75

lowered position of Figure 3 to its upper position of Figure 4, wherein the spring is substantially longer than in Figure 3. Since the pressure exerted by the spring varies directly with its displacement due to load, obviously the pressure exerted by the spring 20 in Figure 4 is substantially less than in Figure 3. Were the pressure which is transmitted to the roller 13 substantially variable with that of the spring, the gravity-overcoming component of that pressure on the sash would correspondingly vary, and such circumstances would result in instability of the sash at one or both of its extreme positions and possibly at intermediate positions, thereby seriously impairing the value of the device.

The invention therefore embodies means for rendering the pressure between the roller 13 and the bearing strip 21 of the sash substantially constant for practical purposes for the range of movement necessary. To this end, the parts are arranged so that the torque about the pivot 8 through the desired range due to the varying forces exerted by the spring 20 is substantially constant. This is accomplished by so arranging the rod 15 relative to the upper arm of the bell crank lever 7 that as the rod 15 is lowered, thus allowing the spring to expand and exert less pressure, the torque arm, that is, the shortest distance from the axis of the rod 15, extended downwardly, to the axis of the pivot 8, increases. The increase in the torque arm is proportional or at least approximately proportional to the decrease in spring pressure, so that the pressure between the roller 13 and the sash 1 is practically uniform notwithstanding the different positions that may be occupied by the sash.

It is to be observed that the pressure from the roller 13, in addition to overcoming the gravity on the sash 1, results in the setting up of (a) static friction which is of sufficient magnitude to prevent movement of the sash merely by virtue of any excess of either the sash weight or the counterbalancing force, and to hold the sash in the desired position until overcome by external force as of a person, and (b) rolling friction which prevents too precipitate a movement of the sash.

In addition to those advantages enumerated, it will be appreciated that the stile edges of a window sash forming part of the construction of the present invention are preserved tight against the jambs of the window frame, because frictional wear on these surfaces through the continued upward and downward movement of the sash is minimized. This means that air currents and/or dust will not tend to leak past the stile edges into the interior of a building wherein my window construction is employed. Again, the various moving parts, including the roller, of my sash-holding mechanism are completely concealed, thereby giving the window structure a neat appearance, as well as obviating accidental injury to these parts or to any one operating the window.

I claim:

1. A sash balancing unit comprising a bracket member having means for securing the same to a jamb of a window frame, a lever pivoted to the bracket member and provided with means arranged to project outwardly beyond the jamb, when the unit is properly mounted, so as to engage the juxtaposed stile of a sash, a bearing member, one of said members having trunnions and the other member having slots for receiving said trunnions, whereby the members may be readily assembled and the bearing member may pivot relative to the bracket member, a part pivoted to

the lever and telescoping said bearing member, and a spring compressed between said bearing member and part so as to hold the members in assembled relation and urge the second means against the stile of the sash.

5

2. A sash-balancing device adapted to be mounted on one of a pair of relatively movable parts and including a spring-pressed member for pressing against an inclined track in a groove in the other part and adapted to be forced from the groove by progressively less deep portions of the track, and means included in said device for retracting and fixing the member out of the groove to enable the parts to be assembled and disassembled.

15

3. In a sash-balancing device, a lever mounted on a support, a roller carried by the lever and adapted to engage a ramp of a relatively movable part, a member pivoted to the lever and slidably engaged with a relatively stationary part of the device so as to constitute with the lever substantially a crank and connecting rod assembly, and a spring for pressing the roller against the ramp, said spring being operatively connected between said lever and said part of the device so that as 25 the spring is progressively stressed by engagement of the roller with progressively shallower portions of the ramp the torque arm at which the spring acts is progressively reduced and vice versa.

30

4. In a sash-balancing device, a lever mounted on a support adapted to be carried by one of a pair of relatively movable parts, a roller carried by the lever for engaging a ramp in a groove in the other part, a rod pivoted to the lever and 35 slidably received by the support, a spring under stress and telescoped with said rod between the support and the lever and arranged so as to urge the roller against the ramp to counterbalance the sash and be stressed by engagement of 40 the roller with less deep portions of the ramp, and means arranged to cooperate with said rod so as to retract the roller to enable the sash to be removed and installed.

5. In a sash-balancing device, a lever mounted 45 on a support adapted to be carried by one of a pair of relatively movable parts, a roller carried by the lever for engaging a ramp in a groove in the other part, a rod pivoted to the lever and slidably received by the support, a 50 spring under stress and telescoped with said rod between the support and the lever and arranged so as to urge the roller against the ramp to counterbalance the sash and be stressed by engagement of the roller with less deep portions of the 55 ramp, and cam means operative when the roller is at the shallow part of the ramp for retracting the roller against the action of the spring to enable the sash to be removed and installed.

6. A sash-balancing device comprising a support, a lever pivoted to the support and provided with means arranged to project outwardly beyond the support, when the unit is properly mounted, for engaging with a member between which and the support there is to be relative movement during such engagement, a part pivoted to the lever and telescopically engaged with the support, a spring under stress between said support and part so as to hold them in assembled relation and urge said means against the member, means for varying the stress of said spring without disturbing the engagement between said means and said member and means for retracting the first means to enable the sash to be installed and removed.

75

7. An assembled pair of upwardly extending relatively movable sash and frame members, one of which has an inclined track forming the bottom of a groove extending in the general direction of relative movement of the members, and the other having a spring pressed part for engaging the track to balance the movable member against gravity, the track, because of its inclination, serving to force said part outwardly 10 relative to the groove upon engagement of said part with progressively less deep portions of the track, and retaining means for fixing said part out of the groove to enable the members to be assembled and disassembled.
- 15 8. In an assembly comprising relatively movable sash and frame members, one of which has an inclined track forming the bottom of a groove extending in the general direction of relative movement of the members, a balancing device 20 mounted on the relatively stationary member, said device including a spring pressed member engageable with the track under spring pressure to balance the weight of the movable member and movable outwardly relative to the groove 25 against the spring pressure, and retaining means included in said device for fixing said member out of the groove to enable the members to be assembled and disassembled, said means being disposed at an edge of the relatively stationary 30 member and being shielded by the relatively movable member except when the relatively movable member is adjacent one limit of its movement.
9. A sash balancing device adapted to be 35 mounted on one of a pair of relatively movable parts and including a member for exerting a counterbalancing pressure on a ramp on the other part, a spring for pressing said member against the ramp and arranged to be placed 40 under increasing stress by progressively less deep portions of the ramp, and means, included in said device, affording a torque arm varying directly with such stress to such an extent as to substantially compensate for the increased spring stress.
- 45 10. In a sash balancing arrangement for sliding sashes, wherein the sash is provided with a stile portion having non-parallel relation with the stile of a frame, movable means for engaging said non-parallel stile portion for an appreciable portion thereof in the normal sliding movements of the sash, means for causing engagement of said movable means with said sash stile portion, the second means exerting a force whose magnitude varies with the respective positions 55 of said sash in said frame, and means for coupling said movable means and said second means for automatically substantially neutralizing the variations in the magnitude of said force.
- 60 11. In a sash balancing arrangement for sliding sashes, wherein the sash is provided with a stile portion having non-parallel relation with a frame stile, movable means for engaging said non-parallel sash stile portion for an appreciable portion thereof in the normal sliding movements 65 of the sash, spring means for causing engagement of said movable means with said sash stile portion, the second means exerting a force whose magnitude varies with the respective positions of
- 5 said sash in said frame, and means having a variable leverage for coupling said movable means and said second means for automatically substantially neutralizing the variations in the magnitude of said force.
12. A sash balancing device adapted to be mounted on one of a pair of relatively movable parts and including a member adapted to exert a counterbalancing pressure on a ramp on the other part, a spring for pressing said member against the ramp and arranged so as to be placed under increasing stress by progressively less deep portions of the ramp, and means included in said device and associated with said spring and member for maintaining a substantially invariable pressure of said member against said ramp independently of the position of said member on said ramp.
13. A sash balancing device adapted to be mounted on one of a pair of relatively movable parts and including a member adapted to exert a counterbalancing pressure on a ramp on the other part, a spring for pressing said member against the ramp and arranged so as to be placed under increasing stress by progressively less deep portions of the ramp, means included in said device and associated with said spring and member for maintaining a substantially invariable pressure of said member against said ramp independently of the position of said member on said ramp, and means for adjusting the spring to enable the device to counterbalance sashes of different weights.
14. An assembled pair of upwardly extending relatively movable sash and frame members, one of which has an inclined track forming the bottom of a groove extending in the general direction of relative movement of the members, and the other having a part for engaging the track, a spring for pressing said part against the track and arranged to be placed under increasing stress by engagement of said part with progressively less deep portions of the track, means associated with said spring and track for maintaining a substantially invariable pressure of said part against said track independently of the position of said part on said track, and means for adjusting the spring to enable the device to counterbalance sashes of different weights.
15. An assembled pair of upwardly extending relatively movable sash and frame members, providing at cooperative stiles thereof an inclined track forming the bottom of a groove in one member and extending in the general direction of relative movement of the members, a gravity counterbalancing pressure device on the other member, said device including a part for engaging the track, a spring for pressing said part against the track and arranged to be placed under increasing stress by engagement of said part with progressively less deep portions of the track, and means included in said device and associated with said spring and track for maintaining a substantially invariable pressure of said part against said track independently of the position of said part on said track.

ABRAHAM SCHNITZLER.
